UNITED STATES PATENT OFFICE.

WILLIAM E. WALSH, OF BUTTE, MONTANA.

AUTOMATIC-DUMPING CONVEYER.

1,104,232.

Specification of Letters Patent. Patented July 21, 1914.

Application filed September 17, 1913. Serial No. 790,239.

To all whom it may concern:

Be it known that I, WILLIAM E. WALSH, a citizen of the United States of America, residing at Butte, in the county of Silverbow and State of Montana, have invented certain new and useful Improvements in Automatic-Dumping Conveyers, of which the following is a specification.

This invention relates to improvements in automatic dumping conveyers.

The primary object of the invention is the provision of a conveyer including a container which is adapted to be automatically actuated for discharging its load at predetermined points in its line of travel.

The present device is adapted for any manner of hoisting purposes whether along a horizontal, vertical or an inclined plane and at any point in which it is designed for automatically dumping its contents. This method of automatically dumping the skip is accomplished by a movement of the same through very little space by dumping from the bottom of this skip and requires a movement of the skip of about one-tenth the distance required by those skips automatically dumping by being turned so that the dumping is accomplished from the top thereof.

One adaptation of this invention to which it is especially designed is the form illustrated in the accompanying drawings which show a self-dumping skip operating in the vertical shaft of a mine for depositing ore either at the top thereof or at transferring levels therein.

A further material object is also to provide swinging trip members at desired levels within the shaft which may be brought into and out of engageable relations with the dumping mechanism of the skip and thereby to dump the latter at such levels when desired. It will be also seen that with this provision the automatic dumping of the skip is accomplished without the possibility of allowing any of the dumped material to fall within the mine shaft.

With these general objects in view and others that will appear as the nature of the invention is better understood, the same consists in the novel combination and arrangement of parts hereinafter fully described, illustrated in the accompanying drawings and pointed out in the appended claims.

In the drawings forming a part of this application and in which like designating

numerals refer to corresponding parts throughout the several views: Figure 1 is a side elevation of one upright of the gallows frame of a mine shaft showing the skip suspended therein. Fig. 2 is a side elevation of the skip as closed and with a trip in its operative relation. Fig. 3 is a similar view of the skip in open position. Fig. 4 is a vertical central sectional view of the closed skip, the bail being broken away. Fig. 5 is a front elevation of the upper portion of the skip, the parts being broken away. Fig. 6 is a top plan view of the skip positioned in the shaft and taken upon the section line 6—6 of the gallows frame as indicated in Fig. 1. Fig. 7 is a transverse sectional view through the skip and frame upon line 7—7 of Fig. 1, and Figs. 8 and 9 are detail views of one of the swinging trips positioned respectively in operative and inoperative positions.

Referring more in detail to the drawings, it is to be understood that the mine shaft is provided with the gallows frame comprising opposite parallel sides 10, only one of the same being shown in Fig. 1 and that the skip 11 for conveying the ore is vertically movable within this frame being elevated by the cable 12 passing over a sheave or drum 13 at the top of the mine and thence communicating with a suitable source of power supply such as a hoisting engine (not shown). The ore receptacle or skip comprises a substantially rectangular bucket 14 with an inclined bottom 15, while a bail member 16 supports the same being reinforced and strengthened by the bottom cross head 17, which is positioned upon the inclined bottom of the skip and secured to the side bail members, a further strengthening being accomplished by the top cross head 18 and to which latter the suspension ring 19 is pivoted and adapted for attachment to said cable 12. The guide strips 20 are vertically positioned upon each side of the frame acting as ways for the skip shoes 21 oppositely arranged upon the outer faces of the bail sides.

The details of the skip construction include operable elements adapted through the engagement of desirably positioned trips to automatically open the skip. The front or longer side wall 22 is fore-shortened for about one-half its length leaving the front opening 23 for the discharge of the skip contents. For closing this exit 23 there is pro-

vided the slide door 24 and the extension apron 25 which act combinedly to open and close the same.

The extension apron 25 is hinged as at 26 to the lowermost front edge of the skip and at a point removed from the center thereof to permit the same to normally assume an open inclined position by reason of its own weight and that of the skip's contents. The 10 slide door 24 is provided with rearwardly extending flanges 27 provided with substantially rectangular strips 28 adapted to engage behind similar strips 29 projecting oppositely at the front of the skip and where- 15 by the door is vertically slidably mounted upon the latter. Angular operating levers 30 are pivoted substantially centrally to the opposite bail sides and provided with their long arms 31 engaging beneath angular 20 flanges 32 of the slide door, the short arms 33 of said levers terminating in anti-friction rollers 34 adapted for automatic operative engagement with the trips hereinafter described upon a vertical movement of the 25 skip.

The side flanges 27 of the slide door are downwardly extended forming opposite feet 35 and whereby the downward movement of the slide door engages said feet rearwardly 30 of the hinging point of the extension apron when the same is opened and by reason of the weight of the slide door operating to tilt upwardly said apron to its closed position.

35 Angular trip irons 36 are permanently positioned at opposite points facing each other upon the gallows frame and adapted to automatically rock the operating levers 30 upon an engagement therewith of the rollers 34 during a vertical movement of the 40 skip.

While the trip irons 30 designed to dump the load at the top or mouth of the shaft are permanently positioned, it is desirable 45 to provide movable trips at points within the shaft and which may be swung at will into and out of operative engagement by said lever rollers 34. For this purpose, leaves 37 hinged as at 38 are oppositely positioned at desired points upon the gallows 50 frame and provided with the trip irons 39. Suitable sockets 40 are mounted upon the frame in proper position to be received through a perforation of each leaf 37 and 55 whereby such leaf may be retained by means of a locking pin 41 in either a closed position as shown by the upper leaf in Fig. 1 or in its open operative position as shown by the lower leaf in said figure.

60 With the skip positioned in the shaft to be vertically hoisted by the cable 12 it will be seen that should it be desirable to dump the ore with which the skip has been filled at a lower point in the shaft at a point short 65 of the top of the mine, such as into a waste

chute at the side thereof, a pair of leaves 37 may be unfastened and swung inwardly of the shaft and thereby engageable by the rollers 34 upon an upward movement of the skip. The engagement with the trips 39 result in shifting the lever, door and apron from their closed positions shown in Fig. 2 to their open positions of Fig. 3 as will be readily apparent, the rocking of the levers 30 upon their pivots by means of the trips 39 raising the slide door 24 to release the apron 25 which of its own weight assisted by the contents of the skip readily opens and forms an exit chute for such contents. Upon such a dumping of the skip contents, a lowering of the latter disengages the trips from the levers allowing the weight of the slide door to close the apron. The leaves 37 may then be swung to their closed positions and retained by the lock pins 41. With the leaves 37 all closed, it is obvious that the skip freely passes the same and moves to a point adjacent the top of the frame where the trips 36 are engaged by the operating levers 30 and the contents dumped at the top 90 of the mine.

It is noted that an elevating of the door 24 releases the apron 25 and that a slight pressure then exerted upon said apron serves to tilt the same beyond the vertical plane of the 95 apron pivot 26 and whereupon its own weight overbalances its upper portion so that the same falls to its open position. This pressure which is necessary for initially tilting the apron is directly accomplished by 100 the contents of the skip whenever there is any material contained therein and generally speaking, an opening of the skip being for dumping purposes, it is primarily necessary only when the skip contains material to be dumped. However, it is desirable to provide a skip which will automatically open at pre-determined positions whether loaded or empty and this is accomplished by linking the door and apron together. Side links 45 are hinged to the apron at its opposite lower 105 corners 46 and have sliding engagement at their upper ends in the slots 47 of the door flanges 27. This mechanism as best shown in Fig. 2, exerts an upward pull upon the links 45 whenever the door is raised and thereby the bottom of the apron is moved rearwardly, and the same becomes thereby overbalanced, resulting in the falling of the 110 apron to its open position as shown in Fig. 3. 115

While the forms of the invention herein shown and described are what are believed to be preferable embodiments thereof, it is nevertheless to be understood that minor changes may be made in the form, proportion and details of construction without departing from the spirit and scope of the invention as set forth in the appended claims.

Having thus fully described my invention and in what manner the same is designed for 125 130

use, what I claim as new and desire to secure by Letters Patent of the United States is:—

1. A skip comprising a body portion, a slide door, a hinged extension apron, and said door adapted upon lowering to actuate said apron upon its hinge.
2. A skip comprising a container, a bail, a front slide door, and pivoted actuating arms adapted for elevating said door to an open position, an extension apron pivotally mounted beneath said door, extension feet upon said door adapted for engaging said apron upon a downward movement of the door and whereby said apron is moved upon its hinge to closed position.
3. A skip comprising an open top receptacle having an exit in the front wall thereof, a door slidably mounted upon said front wall and adapted for partially closing said exit, actuating angular levers pivoted to the opposite sides of said receptacle and adapted upon actuation for elevating said door to its open position.
4. A skip comprising an open top receptacle having an exit in the front wall thereof, a door slidably mounted upon said front wall and adapted for partially closing said exit, actuating angular levers pivoted to the opposite sides of said receptacle and adapted

upon actuation for elevating said door to its open position, an extension apron pivoted to the bottom of said container, said apron adapted to be normally opened and engageable by said door for shifting to its closed position.

5. A skip comprising a container having an open top and a front exit, a slide door and a pivoted apron combinedly closing said exit, pivoted means upon said container engaging said door for sliding the same to open position and automatic means adapted to open said apron simultaneously with the opening of the door.

6. A skip comprising a container having an open top and a front exit, a slide door and a pivoted apron combinedly closing said exit, pivoted means upon said container engaging said door for sliding the same to open position, automatic means adapted to open said apron simultaneously with the opening of the door, and shiftable means positionable in the path of travel of said pivoted means for moving the latter at will.

In testimony whereof I affix my signature in presence of two witnesses.

WILLIAM E. WALSH.
